UNITED STATES PATENT OFFICE.

HOWARD WISWALL, JR., OF WASHINGTON, NORTH CAROLINA.

COTTON-PICKER.

SPECIFICATION forming part of Letters Patent No. 732,681, dated June 30, 1903.

Application filed April 16, 1903. Serial No. 152,938. (No model.)

To all whom it may concern:

Be it known that I, HOWARD WISWALL, Jr., of Washington, in the county of Beaufort and State of North Carolina, have invented a new and useful Improvement in Cotton-Pickers, of which the following is a specification.

My invention is in the nature of an improved cotton-picker of that type in which a flexible pipe with a suction-nozzle on the end is directed by hand to the open cotton-bolls on the plant, which nozzle is provided with picking devices which loosen and detach the cotton, while the suction from a fan carries the fiber up to a suitable receptacle for receiving it.

My improvement comprehends a certain novel and improved construction of nozzle and in the combination and arrangement of the various parts of the machine, as will be first fully described with reference to the drawings and then pointed out in the claims.

In the drawings, Figure 1 is a side elevation; Fig. 2, a plan view; Fig. 3, a rear end elevation, partly broken away. Fig. 4 is an enlarged side view of my improved picking-nozzle, and Fig. 5 is an end view of the same looking in the direction of the arrow in Fig. 4.

The machine is provided with its own motor mechanism for both propelling it across the field and for running its working parts and is guided by means of a man at the steering-wheel after the manner of motor-vehicles. The machine is built as narrow as practicable, so as to run between rows of cotton. It is designed to be stopped in the cotton-field, the gearing changed, and the suction-fan and picking devices started in motion. It is provided with two flexible suction-tubes terminating in picking-nozzles, one on each side, and a man is to hold each picking-nozzle and apply it in his discretion to such of the open cotton-bolls as are ready for picking. When all the cotton in reach is picked, the machine is moved forward to a new position and the picking resumed.

G is a suitable prime motor, preferably a gasoline-engine, mounted upon a platform on wheels. Said engine has its pulley on one side connected by a belt J to a pulley J' on a cross-shaft J². The shaft J² has at each end rigidly-attached sprocket-wheels J³ J³,

which through chain belts J⁴ J⁴ connect with large sprocket-wheels J⁵ J⁵, connected rigidly to the rear running-wheels or their rigidly-attached axle. The pulley J' is loose on the shaft J², but is capable of being locked rigidly thereto by a clutch J⁶, operated by an upright lever L. When this clutch is engaged, the power of the motor is transmitted to the cross-shaft and sprocket-gears to propel the machine across the field, and when the clutch is disengaged the pulley J' runs loose on the shaft.

On the rear part of the platform there is an upright fan-casing A, having within it a suction-fan A'. On the shaft of this fan (see Fig. 2) are a loose pulley N and a fixed pulley O, from which there extends a belt M to a loose pulley N' and a fixed pulley O' on the shaft of the motor. A belt-shifter P embraces the belt and is operated by an upright lever P'. When the belt M is on the two loose pulleys N and N', the fan is not driven, but when the belt is shifted to the two fixed pulleys O and O' the fan is driven. On the fan-shaft there is also a small pulley O², Figs. 2 and 3, connected by a belt O³ with a small pulley O⁴ on the flexible rotating shaft X, extending in bearings along the flexible tube H to the nozzles F, so that this flexible shaft is driven at the same time the fan is. The central opening in the fan-case communicates through a trunk T with a horizontal pipe T', which at each end communicates with the flexible hollow tubes H H to produce a suction of air through the same. Downwardly-dipping pipes P² P² extend from the elevated pipe T' to the rear of the platform at Q, where they discharge the cotton into a bag, basket, or other receptacle hung upon the hooks t t. Valves V V are arranged in the pipe T' and other valves V' V' are arranged in the down-pipes P² P². The discharge from the fan-chamber is through an upwardly-opening stack Y. To prevent the cotton from passing into the fan-chamber, wire screens S S are placed at the upper ends of the down-pipes P², so as to let the air go through them to the fan, while deflecting the cotton down through pipes P². The flexible suction-tubes H and flexible rotating shafts X extend a suitable distance on each side to be manipulated, each

by a man, and be applied to the cotton-plants, and these tubes and shafts terminate in the picker-nozzles. (Best shown in Figs. 4 and 5.) The flexible tube H connects with a low casing K, which opens at its end through a wire screen E, Fig. 5, and the flexible driving-shaft X connects with the axis C, Fig. 4, of a series of picker-saws C', set in a parallel series on a suitable hub. The axial shaft C is carried in suitable bearings and extends through a head of the casing to an outside position, where it couples onto the driving-shaft X, but the saws extend on one side into the interior of the casing through its side. One side of these saws, however, is exposed, so as to be brought into gathering contact with the cotton-bolls by a lateral motion of the picker-nozzles, the plane of the saws being at right angles to the nozzle. As the teeth seize the cotton it is brushed off by a rapidly-revolving brush B, arranged in bearings in the casing upon an axis parallel to that of the saw and extending into range of contact with the saws and projecting also into the cylindrical part of the nozzle-casing, so as to dislodge the cotton from the saws and throw it into range of the incoming draft of air passing in through the screened open end of the nozzle, which carries it up through the tubes H and delivers it into pipes P² and the receptacle provided to receive it. The brush is housed within an enlargement K' of the nozzle-casing and is driven by a small gear-wheel D' at the end meshing with a large gear 35 D on the saw-shaft.

When the machine is not in action or is being transported, the nozzles and tubes H are hung upon suitable supports Z, as seen in Figs. 1, 2, and 3.

I am aware that a cotton-picker provided with a pneumatic suction-nozzle open at the end for the intake of the cotton and having toothed pickers and a brush is not broadly new. My nozzle, it will be seen, is arranged 40 to pick on the side which gives a very extended picking-space and has an open end with wire screen, which does not receive cotton, but allows much of the draft to enter at the end of the nozzle, so as to make a forcible current past the saws, which current whisks the cotton taken laterally by the saws up the tube, and by making a less active current through the cotton itself as it enters the saws avoids drawing in twigs and large impurities into the cotton. As nothing is drawn in except the cotton which touches the saws it will be seen that an expert workman will be able to pick the cotton with my picker 45 with only an infinitesimal amount of trash, which is a consideration of great importance 50 as affecting the value and quality of the cotton.

In practice I prefer saw-shaped picker-teeth; but I would have it understood that I 55 may employ any other form of rotating picker-teeth.

Having thus described my invention, what I claim as new, and desire to secure by Letters Patent, is—

1. A pneumatic cotton-picker, consisting of a nozzle having an open and screened end, a series of rotating picker-teeth arranged in exposed relation along the side of the nozzle upon an axis parallel with the nozzle, and a revolving brush arranged on an axis parallel 75 with that of the rotating picker-teeth and adapted to dislodge the cotton from said teeth and throw it into the incoming draft of air entering through the open end of the nozzle substantially as described.

2. A pneumatic cotton-picker consisting of a nozzle having an open and screened end, a series of rotating picker-teeth arranged in exposed relation along the side of the nozzle upon an axis parallel with the nozzle, a revolving brush arranged on an axis parallel 85 with that of the rotating picker-teeth and intermeshing gear-wheels arranged at right angles to the nozzle on the respective shafts of the brush and rotating picker-teeth substantially as and for the purpose described.

3. A pneumatic cotton-picker consisting of a flexible suction-tube, a flexible drive-shaft arranged in bearings externally to said suction-tube, a picker-nozzle having a casing 95 made larger than the hollow tube, rotating picker-teeth arranged on an axis parallel to the nozzle and extending out through the enlarged casing and connecting externally with the flexible drive-shaft, a rotating brush arranged parallel to the nozzle and gears connecting the shafts of the brush and picker-teeth substantially as described.

4. A pneumatic cotton-picker consisting of a flexible suction-tube a flexible drive-shaft, 105 a picker-nozzle connected to said tube and having a casing with an open end, a laterally-exposed series of saw-teeth arranged on an axis parallel to the nozzle, and a rotating brush arranged within the nozzle-casing to 110 strip the saws and discharge the cotton laterally into the nozzle substantially as described.

5. A pneumatic cotton-picker comprising two suction-tubes with picker-nozzles, a suction-fan with casing inclosing the same, driving mechanism for the same, an elevated and transversely-arranged trunk or tube communicating at opposite ends with the two suction-tubes and with the suction-chamber of the fan in the middle, screens in the elevated horizontal pipe, and down-dipping pipes communicating with the elevated horizontal pipe between the screens and the suction-tubes substantially as and for the purpose 120 described.

6. In a cotton-picker, the combination with a wheeled platform, of an engine mounted on the forward part of the same, a transverse shaft with sprocket-wheels on its ends, 130 chain belts connecting therewith, and large sprocket-wheels embraced and driven by said

chains and rigidly connected to the rear running-wheels, a loose pulley with clutch mounted on the transverse shaft, a belt connecting said pulley to the engine, a rotary suction-fan with fan-casing mounted upon the rear of the platform, a shaft for the fan having loose and fixed pulley, a belt connecting the same to the engine and provided with a belt-shifter, a third pulley on the fan-shaft, a connecting-belt, and a flexible drive-shaft hav-

ing a pulley embraced and driven by said belt, two suction-tubes with nozzles, and picking devices in the nozzles connected to and driven by the flexible shaft substantially as described.
